UNITED STATES PATENT OFFICE.

JACOB VOLPO, OF JERUSALEM, PALESTINE.

SIMPLE REPEATER MECHANISM FOR CLOCKS AND WATCHES.

Application filed April 24, 1923. Serial No. 634,280.

To all whom it may concern:

Be it known that I, JACOB VOLPO, a subject of Spain, residing at Jerusalem, Palestine, have invented a new and useful Simple Repeater Mechanism for Clocks and Watches, of which the following is a specification.

This invention relates to repeater mechanism for timepieces, and more particularly to repeater mechanism in which each stroke of the striking mechanism is made by hand, thus avoiding the necessity for a spring motor with its accompanying speed regulator and cumbersome driving gear.

The general object of the invention is to provide an improved and simplified construction of repeater mechanism of the character above set forth.

An important specific object of the invention is to provide a construction in which the hour striking mechanism is actuated by a toothed rack which is advanced step by step by hand actuated means through a distance determined by means controlled by the time piece.

Another object of the invention is to provide a second toothed rack adapted to be moved by the first toothed rack to actuate a quarter hour striking mechanism.

A further object of the invention is to provide a locking device adapted to lock the mechanism when the toothed rack is fully advanced and capable of being actuated by hand to release the mechanism thereafter when required.

With these and other objects in view, the invention finds embodiment in the construction and arrangement of parts now to be described with reference to the accompanying drawings, in which:—

Fig. 1 is an elevational view of the mechanism in the normal or rest position, and

Fig. 2 is a similar view of the mechanism about to begin the striking operation.

As shown in the drawings, the mechanism comprises a toothed rack 1 mounted to rock about a pivot or arbor 2 under the action of a spring 3. The rack 1 is formed with an arm 4 and is urged by the spring 3 to rock inwardly to bring the arm 4 into engagement with a stepped cam 5 as shown in Fig. 2.

The rack 1 is formed with teeth 6 which are spaced equidistantly along an arc of a circle having its centre at the point 2,

and is adapted to be advanced outwardly step by step against the action of the spring 3 by a hand actuated ratchet device consisting of a pawl 7 pivoted on a lever 8, which is fulcrumed at 8^a; and is formed at its free end with a knob 9. The lever 8 is urged into the position shown in Fig. 2 by a spring 10, but is adapted to be moved into the position shown in Fig. 1 by downward pressure on the knob 9. The pawl 7 is normally held in the position shown in Fig. 2 by a spring 11 on the lever 8, but is capable of being rocked to the right (as seen in the drawings) against the action of the spring 11. As the arm 8 swings downwardly upon depression of the knob 9, the pawl 7 swings bodily about the pivot 8^a, and by engagement with one of the teeth 6 advances the rack 1 outwardly against the action of the spring 3 through the space of one tooth. When the operator releases the knob 9, the arm 8 is returned to the position shown in Fig. 2, and the pawl 7 trips over the tooth 6 next behind that which was engaged by the pawl during the downward movement of the lever 8 and takes up the position shown in Fig. 2 in which it lies clear of the path of the teeth 6.

In order to prevent the rack 1 from being moved inwardly by the spring 3 during the return movement of the lever 8, a pawl 12 is provided, which is fulcrumed at 13 and is urged into engagement with the teeth 6 by a spring 14 acting on a tail 15 formed on the pawl.

The rack 1 is adapted to actuate a striker 16 mounted on a fixed pivot 17 and acted on by a spring 18. The striker 16 is pressed by the spring 18 into engagement with one arm of a bell crank lever 19 controlled by a spring 20, and having an arm 21 lying in the path of the teeth 6. As the rack 1 is advanced through the space of one tooth by the action of the pawl 7, one of the teeth 6 engages the arm 21 of the bell crank lever 19 and rocks the latter, thereby rocking the striker 16 against the action of the spring 18, until the arm 21 stops over the top of the tooth, whereupon the striker 16 is actuated by the spring 18 and the lever 19 is returned to its original position ready for engagement by the next tooth 6.

Carried on the pivot 17 of the striker 16 is a spring loaded pawl 23 adapted to be engaged successively by three equidis-

tantly spaced teeth 24 formed on a rack 25 mounted to rock on a fixed pivot 26 under the control of a spring 27. The rack 25 is also formed with three equidistantly spaced teeth 28 adapted to engage and operate a spring loaded pawl 29 carried by a pivoted striker 30 having an actuating spring 31.

The rack 25 has an arm 32 and is normally urged inwardly by the spring 27 to bring the arm 32 into engagement with a stepped cam 33. A lateral projection 25^a is formed on the rack 25 and is adapted to be engaged by a pin 25^b on the rack 1, whereby the rack 25 is caused to move outwardly with the rack 1 after the last tooth 6 has passed the arm 21.

The stepped cam 33 is driven by the timepiece so that it moves synchronously with the minute hand of the latter and has a pin 34 adapted to actuate a star wheel 35 fast on the shaft of the stepped cam 5, a spring loaded pawl 36 acting to hold the star wheel in any one of a number of definite positions. These parts are similar in construction and operation to those used in many well known forms of striking mechanism for timepieces and need not therefore be described in detail. It is sufficient to state that the inward movement of the rack 1 is limited by the stepped cam 5 so that its subsequent outward movement will actuate the striker 16 once for every complete hour indicated by the hour hand of a timepiece, and that the inward movement of the rack 25 is similarly limited by the stepped cam 33 so that its subsequent outward movement will actuate the strikers 16 and 30 once for every complete quarter of an hour indicated by the minute hand of the timepiece.

In order to enable the racks 1 and 25 to be held normally in their outward positions, a locking member 37 is provided which is adapted to slide on fixed pins 38 working in slots 39 in the locking member. This locking member is provided with a projection 40 and a depending arm 41 and is urged by a spring 42 into the position shown in Fig. 1, in which the lever 8 is locked in the depressed position by the projection 40, and in which the pawl 12 is held in an inoperative position by the engagement of its tail by the finger 41. The locking member 37 is provided with a finger piece 43 whereby it may be shifted by hand into the position shown in Fig. 2 and the parts are so arranged and proportioned that during this movement the release of the pawl 12 will not take place until after the arm 8 has been released. An arm 44 formed on the locking member 37 is adapted to be engaged in the position shown in Fig. 2 by a spring loaded latch 45. This latch is formed with a cam face 46 which is adapted to be engaged by a projection 47 on the rack, the projection 47 being adapted to

release the locking member 37 by rocking the latch 45 when the rack 1 reaches the end of its outward movement.

In operation, the parts are normally in the position shown in Fig. 1, should the user wish to know the time, he first shifts the locking member 37 to the left (as seen in the drawings) by means of the finger piece 43, and brings the locking member into the position shown in Fig. 2, in which position the arm 44 is automatically engaged by the latch 45. This movement of the locking member releases the lever 8 and pawl 12 so that the pawl 7 on the lever 8 is disengaged from the rack 1 whilst the pawl 12 is brought into engagement with the rack 1. As the disengagement of the pawl 7 takes place before the engagement of the pawl 12, as hereinbefore stated, the racks 1 and 25 move inwardly under the action of the springs 3 and 27, before the pawl 12 becomes operative, so that the parts now assume the position shown in Fig. 2.

The user now repeatedly depresses the knob 9, rocking the lever 8 about its pivot and thereby advancing the rack 1 outwardly step by step. This movement of the rack 1 operates the striker 16 through the bell crank lever 19 so that the striker is actuated once for every depression of the knob 9, until the last tooth 6 passes the arm 21. As explained above, the original inward movement of the rack 1 is limited by the engagement of the arm 4 with the stepped cam 5 so that the subsequent outward movement of the rack 1 operates the striker 16 once for every complete hour of the time indicated by the timepiece. When therefore the last tooth 6 has passed the arm 21, the hour of the day has been indicated by the strokes of the striker 16.

As the user continues the repeated depression of the knob 9, the continued outward movement of the rack 1 has no effect, until the pin 25^b on the rack 1 engages the projection 25^a on the rack 25, whereupon the rack 25 is moved outwardly step by step with the rack 1, until it reaches the position shown in Fig. 2. The original inward movement of the rack 25 is limited by the stepped cam 33 as hereinbefore stated, so that the subsequent outward movement of the rack operates the strikers 16 and 30 together once for every complete quarter of an hour indicated by the timepiece.

When the racks 1 and 25 reach the position shown in Fig. 1, the projection 47 on the rack 1 rocks the latch 45 by engagement with the surface 46 thus releasing the locking member 37, which is then moved by its spring 42 into the position shown in Fig. 1. This movement of the member 37 rocks the pawl 12 by engagement of the finger 41 with the tail 15, and when the lever 8 reaches the position shown in Fig.

1, the projection 40 engages and locks the lever. The parts are thus brought into the rest position shown in Fig. 1.

By releasing the locking member 37, the 5 user can now repeat the operations described above, and this can be done as often as desired. It will thus be seen that the user can ascertain the time by operating the mechanism and counting the strokes made 10 by the strikers 16 and 30 whenever he so desires.

Although I have described but one embodiment of my invention, it will readily be appreciated that many detailed modifications could be made without departing from the spirit of the invention. It is therefore to be understood that I do not propose limiting myself to the exact construction and operation above described and particularly 20 that I do not limit myself to the specific periods of time described as being indicated by the strokes of the strikers 16 and 30, but may vary these to suit requirements.

I claim:

25 1. In a repeater mechanism for time-pieces, a toothed rack movable towards an outward position, hand actuated means for advancing said rack toward its outward position step by step, striking mechanism actuated by the step by step movement of said rack, a locking member movable to engage and lock said hand actuated means when said rack reaches its outward position, said locking member being movable by hand into 30 inoperative position for disengaging said hand actuated means, yielding means urging said rack inwardly, means for freeing said rack for inward movement when said locking member is moved to inoperative position and means controlled by the time-piece for limiting the inward movement of 35 said rack.

2. Repeater mechanism for timepieces according to claim 1 including a second 40 toothed rack movable towards an outward position, yielding means urging said second rack inwardly, means controlled by the time-piece for limiting the inward movement of said second rack, striking mechanism actuated by said second rack and an operative connection between said second rack and said first mentioned rack.

3. In a repeater mechanism for time-pieces, a toothed rack movable from an inward position to an outward position, means controlled by the timepiece for determining said inward position, a hand actuated ratchet device co-operating with the teeth of said rack for advancing said rack outwardly, 45 said device being movable from an advanced position to a retracted position in which it clears the path of the teeth of said rack, striking mechanism actuated by said rack, a spring urging said rack inwardly, means 50 normally preventing inward movement of

said rack and hand actuated means for freeing said rack for inward movement.

4. In a repeater mechanism for time-pieces, a toothed rack movable from an inward position to an outward position, means 55 controlled by the timepiece for determining said inward position, hand actuated means for advancing said rack from said inward position to said outward position, step by step, striking mechanism actuated by the 60 step by step movement of said rack, a second toothed rack also movable from an inward position to an outward position, means controlled by the timepiece for determining 65 said inward position, a lost motion connection between said second rack and said first mentioned rack for advancing said second rack step by step, and striking mechanism actuated by the step by step movement of 70 said second rack.

5. In a repeater mechanism for time-pieces a toothed rack movable towards an outward position, a spring for urging said rack inwardly, a hand actuated ratchet device for advancing said rack outwardly, a 75 pawl for preventing inward movement of said rack, striking mechanism actuated by said rack, a hand actuated locking member having a locking position and a release position and means on said locking member for 80 retracting said pawl and locking said ratchet device when said locking member is in the locking position.

6. A repeater mechanism according to 85 claim 1, wherein said locking member has a locking position and a release position, including a spring for urging said locking member towards locking position, a latch for holding said locking member in release position and means on said rack for releasing 90 said latch.

7. In a repeater mechanism for time-pieces, a rack movable towards an outward position, a spring urging said rack inwardly, means controlled by the timepiece for 100 limiting the inward movement of said rack, a hand actuated ratchet device co-operating with the teeth of said rack for advancing said rack outwardly, said device being movable from an advanced position to a retracted position in which it clears the path 105 of the teeth of said rack, a pawl for preventing inward movement of said rack, striking mechanism actuated by said rack, a hand actuated locking member having a locking position and a release position, 110 means on said locking member for locking said ratchet device in the advanced position when said locking device is in the locking position, means on said locking member for 115 rendering said pawl inoperative until after said ratchet device is released, a spring urging said ratchet device towards the retracted position, a spring urging said locking member toward the locking position, a latch for 120

holding said locking member in the release position and means on said rack for releasing said latch when said rack reaches its outward position.

8. A repeater mechanism according to claim 7 including a second toothed rack movable towards an outward position, striking mechanism operated by said second rack, means for operating said first mentioned

striking mechanism by said second rack, a 10 spring urging said second rack inwardly, means controlled by the time piece for limiting the inward movement of said rack, and a lost motion connection between said second rack and said first mentioned rack for 15 advancing said second rack outwardly.

JACOB VOLPO.
